176,902

FORK OR SIMILAR ARTICLE OF FLAT SILVER

Mark H. Blair, East Providence, R. I., assignor to The Watson Company, Attleboro, Mass., a corporation of Massachusetts

Application May 11, 1955, Serial No. 35,920

Term of patent 14 years

(Cl. D54—12)

Fig. 1.

Fig. 3.

Fig. 2.

Fig. 4.

Fig. 5.

Fig. 1 is a front elevational view of a fork, showing my new design;

Fig. 2 is a side view thereof;

Fig. 3 is a transverse sectional view on line 3—3 of Fig. 1;

Fig. 4 is a transverse sectional view on line 4—4 of Fig. 1; and

Fig. 5 is a transverse sectional view on line 5—5 of Fig. 1.

The essential features of the design reside in the parts shown in full lines on the drawing.

I claim:

The ornamental design for a fork or similar article of flat silver, substantially as shown and described.
